CLAIM

We claim the ornamental design for a frontload drying
appliance, as shown and described.

DESCRIPTION

FIG. 1 is a first top perspective view of the frontload drying
appliance of the present invention;

FIG. 2 is a second top perspective view of the frontload
drying appliance of the present invention;

FIG. 3 is a top plan view of the frontload drying appliance
of the present invention;

FIG. 4 is a bottom plan view of the frontload drying
appliance of the present invention;

FIG. 5 is a first side elevation view of the frontload drying
appliance of the present invention;

FIG. 6 is a second side elevation view of the frontload drying
appliance of the present invention;

FIG. 7 is a third side elevation view of the frontload drying
appliance of the present invention; and,

FIG. 8 is a fourth side elevation view of the frontload drying
appliance of the present invention.

The broken lines shown in the figures are for the purpose of
illustrating unclaimed portions of the frontload drying appli-
ance, and form no part of the claimed design.
